Filed Sept. 17, 1968, Ser. No. 13,564

Term of patent 14 years

Int. Cl. D23—03, 04

U.S. Cl. D23—77

FIG. 1 is an isometric view of the top and front of an electric solder pot embodying the design of my invention;

FIG. 2 is a front elevational view of this solder pot;
FIG. 3 is a top plan view of this solder pot; and
FIG. 4 is a bottom plan view of this solder pot.

The rear and sides of the solder pot are identical to the front except for the omission of the scale, the projections at each end of the scale and the pointer.

I claim:

The ornamental design for an electric solder pot, substantially as shown and described.
